ELECTRIC CIRCUIT BREAKER

Robert T. Casey, Bristol, Conn., assignor, by
mesne assignments, to General Electric Company, a corporation of New York

Application September 29, 1949, Serial No. 118,518

10 Claims. (Cl. 200—88)

1 It is well known that in interrupting alternating currents, a great variation occurs in the intensity of the arc, the amount of flame issuing from the breaker, the damage to the casing and metal parts, danger to personnel, and fire hazard during different interruptions, due to the fact that with conventional breakers, the separation of the contacts and hence the drawing of the arc, is liable to occur at various points in the current cycle. If it happens to occur when the current is just nearing its peak, all of these factors will be at or near a maximum. If it occurs when the current is close to zero, these factors will be at a minimum.

In the past this has depended entirely on chance. It is an object of the present invention to provide a circuit breaker which shall open at a predetermined low point in the alternating current cycle.

It has been attempted in the past to make a circuit breaker of this type as in Patents No. 1,814,847 and No. 1,805,497, W. E. Paul. These, however, have attempted to operate directly on the contacts rather than on the releasing mechanism. They are moreover related to large oil breakers, whereas the present invention is an adaptation to the simple structures of small air circuit breakers.

The drawings disclose a magnetically responsive means for releasing the trip-restraining element of a circuit breaker. It will be seen from the nature of this and similar circuit breakers, that when in the "on" condition there is a constantly maintained force tending to cause automatic opening of the contacts. This force is restrained from acting by a "latch" which is movable to a releasing position to allow tripping or automatic opening to occur.

By the present design I cause the circuit breaker at one point in the tripping thereof, to be held momentarily in the "on" position by magnetic force despite the fact that it may be unlatched by other overload responsive action.

The accompanying drawing show circuit breakers embodying two forms of my invention.

Fig. 1 is a face view of one form of circuit breaker with the parts in the closed circuit or "on" position.

Fig. 2 is a fragmentary cross section taken on the plane of the line 2—2 of Fig. 1.

Fig. 3 is a face view of another form of circuit breaker with the parts in full lines in open circuit position and in dotted lines in the closed circuit position.

Fig. 4 is a fragmentary sectional view of the 55

latching parts of Fig. 3 taken along the line 4—4 of Fig. 3.

The housing may be formed of two parts of insulation 5 held together in any suitable manner.

5 Circuit terminal members 6 and 7 are suitably mounted at opposite ends of the housing.

One of the switch contacts 8 is formed on the inner end of terminal member 6 and the movable switch member 9 is hinged at 10 on the cradle or trip arm 11 which is hinged at 12 in the housing.

10 The actuating handle rocker member 13 is hinged in the housing at 14 and a spring 15 connects this member from 16 to the switch member 9 at 17.

The tension of spring 15 draws switch member 9 against the shoulder 18 of the cradle 11 so as to bias the cradle anti-clockwise.

15 Member 13 has a lug 19 which engages the shoulder 19' on the cradle 11 when opening the circuit manually.

Member 13 has a lug 19 which engages the shoulder 19' on the cradle 11 when opening the circuit manually.

20 Terminal member 7 has an extension arm 20 to which the bimetal thermostatic strip 21 is secured. A calibrating screw 22 is rotatably mounted in the housing and threaded in the end of arm 20 as more fully described in my application Serial Number 91,085, filed May 3, 1949, now Patent No. 2,573,307. A flexible conductor 23 connects the strip 21 with the switch member 9.

25 The thermostatic release member 21 has a catch member 24 which is normally engaged by a latch member 25 pivotally mounted on the trip arm 11.

30 To open the circuit manually it is only necessary to throw the actuating lever 13 toward the right whereupon the toggle action of the spring 15 will throw the switch member 9 to the "off" position in a well known manner. The circuit may be closed manually by moving the lever 13 back to the left.

35 In case of an overload, the strip 21 is heated and warps so as to withdraw the catch 24 from the latch 25 and permit the spring 15 to tilt the cradle or trip arm 11 counter-clockwise and carry the hinge point 10 across the center line of the spring 15 by well known toggle action and thus open the circuit.

40 To release the switch in case of a heavy surge of current, I provide an electromagnetic device comprising a field piece 26 and an armature 27 formed as an oppositely extending arm on the pivoted latch 25, the armature 27 and latch lever 25 constituting a bell crank pivoted at 28 on the trip arm 11. The conductor 23 is clamped

between the poles of the magnet 26 by a non-magnetic plate 29 (Fig. 2) so that the magnet is energized by a heavy current passing between the poles of the magnet clockwise about its pivot support 28. The spring 30 biases the armature away from the magnet and tends to engage the latch 25 with the release catch 24. Shoulder 31 on the end of the cradle limits the clockwise turning movement of the armature and the latch.

When the magnet is energized the armature 27 is drawn down and the latch 25 released from the catch 24. It will be seen, however, that although the latch 25 is released, the cradle 11 cannot turn counterclockwise as long as the armature 27 is held down by the magnetic force. Spring 15 tends to turn the cradle 11 counterclockwise. As long as the holding force of the magnet 26 is strong enough to overcome the effect of spring 30 no automatic opening can take place. When the magnetic pull decreases to a point where it is less than the effective pull of spring 15 the cradle 11 will be released and rotate counterclockwise and open the circuit.

It is well known that the holding-in force of an electro-magnet greatly exceeds its maximum pull. In order to take advantage of this holding-in force, I may provide that the relation between the attractive movement of armature 27 and the amount of latch overlap at 24 is such that even when the armature 27 is fully in engagement with magnet 26, the latch 25 will not be released until the bimetal 21 moves back a short distance. With this arrangement, it will be assured that armature 27 will engage the magnet 26 before the catch 24 releases the latch 25. The magnetic holding force will then hold the trip arm 11 against movement even after latch release until the current approaches zero.

By reason of the residual magnetism the holding force of the magnet 26 will not reach absolute zero value until the current has reversed its direction and reached some new value. The time which elapses between release of the magnet and opening of the circuit may vary depending upon the weight, inertia and speed of movement of the associated parts. The dimensions and material of the magnet 26 and its armature 27 may in any given case be so chosen therefore that the point in the cycle of current at which the magnet releases will be such that the contacts will separate at or near the zero current point. When the magnet 26 finally releases its armature 27 the cradle or trip arm 11 is free to rotate anti-clockwise by the toggle action of spring 15 and switch member 9.

When it is called to mind that the current in this type of breaker is normally called upon to interrupt is an alternating current, which is continually varying from a maximum to a zero value, and that even under short circuit conditions a surge of excess current will be followed by a reduction of current to the zero point, it will be seen that should a short circuit occur while the current is building up to its maximum value, armature 27 will pull in and will hold cradle 11 from rotating and hence prevent the contacts from opening until the current again decreases to a value low enough so that the magnetic pull of the magnet is too small to hold the cradle, at which time the cradle will be released.

It will, therefore, be seen that the contacts will open at or near a time when the varying current is zero. The breaker will, therefore, not be called upon to interrupt a high current, nor will there be the characteristic flame and damage

caused by a large arc. The life of the breaker will also be considerably lengthened.

It should be noted that this design also permits the magnetic trip to have the desired release-delaying action without interfering with the normal operation of the bimetal trip on small overloads.

The form of my invention disclosed in Figs. 1 and 2 is described and claimed in my copending continuation-in-part application Serial Number 237,256, filed July 17, 1951.

The form shown in Figs. 3 and 4 shows a form of circuit breaker in which a minimum current magnetic tripping action is combined with a manual operation as well as a thermostatic release.

Any suitable circuit terminals such as 36 and 37 may be mounted in the housing 35. The housing 35 is a two-part housing, as is the housing 5 of Fig. 1, the housing parts being suitably recessed to receive the operating parts and each housing member being the mirror image of the other. Stationary contact 38 and movable contact 39 constitute the switch members. The switch member 39 is hinged at 40 in the cradle or tripping member 41 which is suitably hinged at 42 in the housing parts 35.

The manually operable handle rocker 43 is hinged at 44 and connected by spring 45 from 46 on the rocker to the switch member 39 at 47. The handle rocker 43 has a lug 48 for engaging the cradle 41 and operating the switch by a conventional toggle action.

Terminal 37 has a supporting member 50 suitably secured to the housing 35 to which the upper end of a thermal-responsive bimetal strip 51 is secured and in which a calibrating screw 52 is adjustable. This strip 51 is connected by a flexible conductor 53 to the hinged switch member 39.

A magnet field piece 55 is mounted on the strip 51 and consequently moves with it. An armature 56 is hinged at 57 in suitable recesses in the housing halves 35. The spring 58 biases the armature 56 away from the field piece 55.

A non-magnetic spring latch member 60 is supported by member 59 and has a loose connection at 61 with the movable end of bimetal strip 51 the latch member 60 being slotted at its lower end to receive the bimetal strip 51. This latch member 60 extends between the armature 56 and the field piece 55 and has a bent tip 62 forming a latch which extends into normal latching engagement with a shoulder 63 on the end of the cradle 41 (Figs. 3 and 4).

In case of a slow overload the bimetal strip 51 warps toward the bight of the magnet 55, draws over the spring latch member 60 and releases the tip 62 from the cradle 41, the cradle 41 then moving to open the circuit in the usual manner. During this operation the spring 58 holds the armature to the left against a suitable stop (not shown) formed in the casing 35.

In case of a high current or heavy surge of current, the magnet is energized to draw the armature and latch arm 63 toward the field piece 55, the armature engaging and moving the lower end of the latch arm 63 so as to release the cradle or trip arm 41. In this case, however, the stop or latch 64 on the armature has been moved with the armature to a position in which the latch 64 is interposed in the path of movement of the shoulder 65 on the trip arm 41, and after a slight initial movement upward of the trip arm past the latch 62, the shoulder 65 engages the stop 64 and

brings the trip arm to rest. The trip arm is held by the shoulder 65 until the instantaneous value of the current in the circuit breaker, which current flows through the bimetal strip, decreases sufficiently to de-energize the magnet and permit the spring 58 to move the armature back to its unattracted position shown in Figs. 3 and 4, and thereby disengage the stop 64 from the shoulder 65 of the trip arm whereupon the trip arm moves upward in accordance with its bias to open the circuit breaker.

It will be seen, from the above described operation, that the magnet 55 has to exert only enough force to overcome the bias of the armature-bias-spring 58 and to move the armature 56 to the closed position. It is not called upon, as in the first form, to overcome the force of the main operating spring, in order to maintain the breaker in the closed position.

The releasing action achieved by this latter structure is of the two-step type. When a small overload occurs, only the first step is necessary in order to release the breaker. When a relatively large overload occurs (so as to actuate the magnet) two steps are necessary, i. e., the main latch must release, and the auxiliary or secondary latch must release.

I claim:

1. In a circuit breaker, a trip member biased to an open circuit position, a latch normally holding said trip member in a closed circuit position, electromagnetic means provided with an armature movable to an attracted position in response to a high current in the circuit breaker for moving said latch to release said trip member, and a connection between said armature and said trip member for holding said trip member until said armature is released for movement upon a decrease in current.

2. In a circuit breaker, a trip member biased to an open circuit position, a first latch normally holding said trip member in a closed circuit position, electromagnetic means provided with an armature biased to an unattracted position and movable in response to a high current in the circuit breaker for moving said first latch to release said trip member, and a second latch moved by said armature into the path of said trip member so as to restrain said trip member until the current has decreased to permit the return of said armature to its unattracted position.

3. In a circuit breaker, a trip member biased to an open circuit position, a latch member normally restraining said trip member, electromagnetic means responsive to the current in the circuit breaker provided with an armature biased to an unattracted position and movable in response to a high current for moving said first latch to release said trip member for an initial movement, and a latching projection on said armature for restraining of said trip member until the current has decreased to permit the return of said armature to its unattracted position.

4. In a circuit breaker, a trip member biased to an open circuit position, a latch normally holding said trip member in a closed circuit position, electromagnetic means energized by the current in the circuit breaker provided with an armature biased to an unattracted position, an operating connection between said armature and said latch for moving said latch to release said trip member when said armature is moved to an attracted position in response to a high current, and a second latch moved by said armature to hold said trip member after said trip member is released by said

first latch until said armature returns to its unattracted position in response to a decrease in the current in the circuit breaker.

5. In a circuit breaker, a trip member biased to an open circuit position, a latch normally holding said trip member in a closed circuit position, a magnet field piece, means responsive to the current in the circuit breaker for energizing said field piece, a movably mounted armature for said field piece, a spring for biasing said armature to an unattracted position, an operating connection between said armature and said latch for moving said latch to release said trip member when said armature is moved toward said field piece to an attracted position in response to a high current, and a second latch moved by said armature into the path of said trip member when said armature moves to its attracted position so as to hold said trip member after it is released by said first latch until said armature is moved by said spring upon a decrease in the current in said energizing means.

6. In a circuit breaker, a trip member biased to an open circuit position, a spring latch arm having a latching projection for engaging and holding said trip member in a closed circuit position, a magnet field piece, current conducting energizing means for said field piece connected in circuit with said circuit breaker, a movably mounted armature for said field piece, a spring for biasing said armature to an unattracted position, an operating connection between said armature and said latch arm for moving said latch arm to release said trip member when said armature is moved toward said field piece to an attracted position in response to a pre-determined high current, and a projection on said armature movable into the path of said trip member when said armature moves to its attracted position so as to stop said trip member after an initial movement and hold said trip member until said armature is moved by said spring to its unattracted position upon a decrease in the instantaneous value of the current in said energizing means.

7. A circuit breaker having circuit making and breaking mechanism, a trip member for said mechanism biased to an open circuit position, a latch arm for holding said trip member, a bimetal thermostatic strip, means for heating said bimetal strip in response to the current in the circuit breaker, a magnet field piece carried by a movable end of said bimetal strip, a spring biased armature for said field piece for engaging and moving said latch arm in response to a high current thereby to release said trip member, a latching projection on said armature movable into the path of said trip member when said armature moves to its attracted position thereby to stop said trip member after an initial movement and hold said trip member until said armature returns to its unattracted position upon a decrease in current, and an operating connection between said bimetal strip and said latch arm for movement of said latch arm by said bimetal strip in response to a low current in the circuit breaker.

8. A circuit breaker having circuit making and breaking mechanism, a trip member for said mechanism biased to an open circuit position, a spring latch arm having a latching projection for engaging and holding said trip member, a bimetal thermostatic strip, means mounting adjacent ends of said latch arm and said bimetal strip so that they extend in substantial parallel adjacent relation with each other, means for

heating said bimetal strip in response to the current in the circuit breaker, a magnet field piece carried by the movable end of said bimetal strip, a spring biased armature for said field piece on the opposite side of said latch arm from said field piece so that said latch arm is engaged by said armature in moving in response to a high current to an attracted position thereby to release said trip member, a latching projection on said armature movable into the path of said trip member when said armature moves to its attracted position thereby to stop said trip member after an initial movement and hold said trip member until said armature returns to its unattracted position upon a decrease in current, and an operating connection between said bimetal strip and said latch arm for movement of said latch arm by said bimetal strip in response to a low current in the circuit breaker.

9. In an alternating current circuit breaker having circuit making and breaking mechanism, a movable trip member for said mechanism biased to an open circuit position, latch means including a bimetallic strip heated in response to the current in said circuit breaker, said latch means normally restraining movement of said trip member and releasing said trip member in response to predetermined overload current heating of said bimetallic strip, magnetic means including an armature movable to an attracted position in response to a predetermined overload current to at least partially release said latch means independently of said bimetallic strip and

to hold said trip member against movement, said armature moving to an unattracted position upon instantaneous current decay and releasing said trip member for movement to open said circuit breaker.

10. In an alternating current circuit breaker having circuit making and breaking mechanism, a movable trip member for said mechanism biased to an open circuit position, latch means including a bimetallic strip heated in response to the current in said circuit breaker, said latch means normally restraining movement of said trip member and releasing said trip member in response to predetermined overload current heating of said bimetallic strip, magnetic means including an armature movable to an attracted position in response to a predetermined overload current to release said latch means independently of said bimetallic strip and to hold said trip member against movement, said armature moving to an unattracted position upon instantaneous current decay and thereby releasing said trip member for movement to open said circuit breaker.
